MICROPHONE

Hajime Ota, Tokyo, Japan, assignor to Fedtro, Inc.,
a corporation of New York

Filed Oct. 22, 1965, Ser. No. 87,774

Term of patent 14 years

(Cl. D26—14)

FIG. 1 is a top plan view of a microphone, showing my new design;

FIG. 2 is a bottom plan view;

FIG. 3 is a front elevational view;

FIG. 4 is a rear elevational view;

FIG. 5 is a right side elevational view; and

FIG. 6 is a left side elevational view thereof.

I claim:

The ornamental design for a microphone, substantially as shown.
